(57) **CLAIM**

The ornamental design for a lint roller, as shown and described.

DESCRIPTION

FIG. 1 is a front, right, top perspective view of a lint roller in the first state, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 2;

FIG. 10 is an enlarged view of detail 10 in FIG. 3;

FIG. 11 is an enlarged view of detail 11 in FIG. 8;

FIG. 12 is a front, right, top perspective view of the lint roller in the second state; and,

FIG. 13 is a rear, left, bottom perspective view of the lint roller in the second state.

The dashed broken lines illustrate portions of the lint roller which form no part of the claimed design.

The dash-dot-dash broken lines are for notating enlarged views and form no part of the claimed design.
